DISPENSER

Benona F. Mannen, Sarnia, Ontario, Canada

Application February 27, 1934, Serial No. 713,232

4 Claims. (Cl. 123—196)

This invention relates to a dispenser especially adapted for supplying lubricant in the form of powder or flaked graphite to an engine whereby the various moving parts or the surfaces of such parts of said engine may be coated and the pores of the metal of the parts filled with graphite to assure a maximum lubrication and reduce wear to a minimum, and has for the primary object the provision of a device of the above stated character which may be easily and quickly installed to the intake manifold of an engine so that the proper amount of graphite lubricant may be drawn into the engine and become mixed with the ordinary lubricant and thereby permit coating of the metal of the moving parts of the engine, such as the valves, walls of the cylinders, pistons, piston rings and bearings with graphite.

With these and other objects in view this invention consists in certain novel features of construction, combination and arrangement of parts to be hereinafter more fully described and claimed.

For a complete understanding of my invention, reference is to be had to the following description and accompanying drawing, in which

Figure 1 is a vertical sectional view illustrating a dispenser constructed in accordance with my invention.

Figure 2 is a sectional view taken on the line 2—2 of Figure 1.

Figure 3 is a sectional view taken on the line 3—3 of Figure 1.

Figure 4 is a detail sectional view illustrating an air control valve.

Figure 5 is a detail sectional view illustrating an outlet jet for the device.

Referring in detail to the drawing, the numeral 1 indicates a bowl or container having a rounded bottom wall and a fully open upper end flanged, as shown at 2, to provide a seat for a gasket 3 engaged by a removable cover 4 preferably constructed of a transparent material. The cover is held against the gasket by a pivoted ball 5 carried by the container 1 and providing a construction which will permit the cover to be easily removed when desiring to place in the bowl or container graphite in powdered or flake form.

The bottom wall of the bowl or container is provided with a screw threaded opening in which is mounted a nipple 6 having a bore 7 terminating into a restricted orifice 8 located at the inner end of the nipple for the purpose of admitting a small volume of air to the interior of the bowl or container when a suction is created therein. The bottom wall of the container or bowl also has

threaded thereto an adjusting screw 9 engageable with a collar 10 carried by the lower end of a tube 11 arranged vertically within the container or bowl and supported in said position by fins 12 engaging the walls of the container. The lower end of the tube 11 may be adjusted towards and from the inner end of the nipple 6.

An outlet nipple 13 is threaded in a port formed in the bowl or container adjacent the upper end of the latter and has connected thereto a fitting 14 to which a pipe or tube 15 is connected and the latter is connected to the intake manifold of an engine. The outlet nipple 13 has a bore 16 terminating into a restricted orifice 17 located at the inner end of the nipple and within the bowl or container.

Arranged opposite to the nipple 16 and within a port of the bowl or container is a control valve 18 for the purpose of admitting to the bowl or container an additional amount of air over that received from the nipple 6 when a suction is developed in said bowl or container. The control valve may be adjusted to regulate the amount of the auxiliary supply of air. The control valve 18 is preferably of the needle type construction, as shown in Figure 4.

A suitable bracket 19 is detachably secured to the bowl or container 1 and is equipped with bolts or like fasteners 20 for attaching the bracket to a suitable part of the engine or to some part of an automobile when the engine is employed in such a vehicle.

In operation, powdered or flaked graphite is placed in the container or bowl 1 leaving the upper end of the tube 11 exposed or uncovered by the graphite. The engine while in operation will create a suction in the bowl or container and this suction draws air into the bowl or container and which air passes upwardly through the tube and the graphite between the lower end of the tube and the nipple 6 is forced upwardly through the tube into the upper portion of the bowl or container. Particles of the graphite thus become suspended in the air and will pass into the engine through the outlet nipple 16 and pipe 15. The particles of graphite thus entering the engine through the intake manifold will thoroughly coat or lubricate the valves, pistons, piston rings and walls of the cylinders, also some of the graphite will become mixed with the ordinary lubricant of the engine and be carried to the other various moving parts of the engine thereby coating their surfaces. The amount of graphite admitted to the engine can be controlled by the adjustment of the tube 11 and the nipple 6 and also by regu-

lating the amount of air admitted by the control valve 18.

Having described the invention, I claim:

1. A dispenser comprising a container, means for connecting the container to the intake manifold of an engine, means for admitting air to the lower end of the container, and a tube adjustably mounted in the container and capable of being moved towards and from said second means.
- 10 2. A dispenser comprising a container, a removable cover for said container, means for connecting the container to the intake manifold of an engine, air admitting means at the lower end of the container, a tube adjustably mounted in the container and capable of being moved towards and from the air admitting means.
- 15 3. A dispenser comprising a container, a removable cover for said container, means for connect-

ing the container to the intake manifold of an engine, air admitting means at the lower end of the container, a tube adjustably mounted in the container and capable of being moved towards and from the air admitting means, and an air control valve for the container.

4. A dispenser comprising a container, an outlet nipple connected to the container, means for connecting said nipple to the intake manifold of an engine, an air inlet nipple located at the lower end of the container, a tube arranged vertically within the container, means for adjusting the tube towards and from the air admitting nipple, fins carried by said tube and contacting with the walls of the container, and an air regulating valve carried by the container.
